UNITED STATES PATENT OFFICE

VASCO DA GAMA, OF NEW YORK, N. Y.

DESIGN FOR A TABLE LIGHT OR ANALOGOUS ARTICLE

Application filed May 28, 1932. Serial No. 43,922. Term of patent 7 years.

To all whom it may concern:

Be it known that I, VASCO DA GAMA, a citizen of the Republic of Spain, residing at the city, county, and State of New York, have invented a new and useful, original, and ornamental Design for Table Light or Analogous Article, of which the following is a specification, reference being had to the accompanying drawing, forming part thereof.

Figure 1 is a front view of a table light or analogous article showing my new design, and

Figure 2 is a side view thereof.

I claim:

The ornamental design for a table light or analogous article, as shown.

VASCO DA GAMA.
